AIR VENT VALVE

Edward J. Zeitlin, Yorktown, N. Y.

Application March 3, 1949, Serial No. 79,409

2 Claims. (Cl. 236—64)

1

This invention relates to valves and more particularly to air vent valves for steam heating systems. The valve more particularly belongs to a class of valves which permit expulsion of air from the system under action of internal pressure generated by the expanded vapors. Furthermore, the valve is arranged to close automatically when the hot vapors contact the thermostatic element. The air port valve closes automatically to prevent re-admission of air when the internal pressure of the system is below atmospheric pressure and thus a partial vacuum is maintained.

One of the objects of this invention is to provide an air vent valve of the type that permits varying the rate of discharge of air from various sections in the heating system in accordance with the venting requirements or volume of air to be eliminated to balance the rate of admission of steam to the radiators in the various sections of the heating system.

Another object of this invention is to provide an air vent valve that permits the egress of air from the heating system when the steam pressure in the system rises and prevents the ingress of air back into the heating system when the steam pressure in the system drops.

A still further object of this invention is to provide an adjustable air vent in the valve to vary the rate of egress of air from the valve so as to balance the venting of the various sections of a heating system.

A still further object of this invention is to provide an air check valve that is normally open, and said valve being closed by atmospheric pressure when the internal pressure within said valve is less than atmospheric.

Other objects of this invention may be apparent by reference to the accompanying description and the drawing in which

Fig. 1 is a front elevational view of the valve,
Fig. 2 is an exploded view of the valve shown partly in cross section.

Fig. 3 is a plan view taken on line 3—3 of Fig. 2,
Fig. 4 is a plan view taken on line 4—4 of Fig. 2, and

Fig. 5 is a cross sectional view of the butterfly valve.

Referring to Figs. 1 and 2 there is illustrated a valve 10 which is comprised of a base portion 11, that supports the valve structure and is provided with threaded exterior and interior means for affixing said valve to the heating system. The valve 10 is also provided with an exterior barrel shaped housing 12 and a top or cap member 14. A thermostatic element 15 (in this case con-

structed in the form of a sealed bellows that is common in the art) is mounted within the valve housing and the bellows 15 is provided with an extended threaded member 16 that is threadably secured in a socket 17 in the cap member 14. An air port disk 18 is also threadably secured to the extended member 16 and a butterfly valve 19 is affixed to the upper surface of the disk 18 by means of a pair of loose fitting rivets 20 and 21 providing a hinged support. The bellows member 15 on its lower surface is formed with a valve face 22. The valve face is shaped to mate with a cone shaped valve seat 23 formed in the interior of base member 11. A port 24 connects the valve seat 23 with the exterior of the base 11. The opposite end of the base 11 is provided with a threaded opening 25 to permit threadably securing the housing 12 thereto. The housing 12 is provided with an external thread 26 at its base and is also provided with a cutout portion 27 at its upper periphery. A stop 28 is threadably secured in a socket in the housing 12 and projects outwardly and is adjacent to the cutout portion 27. Referring to the cap member 14, it may be noted that approximately half of this element is hollowed out so that the cap member will fit down over the exterior of the member 12 and the cap member 14 is provided with an elongated slot 34 adjacent the lower edge of the cap 14.

Referring to Figs. 3, 4 and 5, we may see the construction of the air port and butterfly valve. Fig. 3 illustrates the butterfly valve 19. Fig. 4 illustrates the disk member 18 and it may be noted that a pair of apertures 29 and 30 are provided in the valve 19 to align with a pair of apertures 31 and 32 in the disk 18. Thus with the pins 20 and 21 mounted through these aligned apertures, the pins may be fastened in any manner such as riveting, but in such fastening the element 19 must be loosely held to permit a rocking action as illustrated in Fig. 5 so that in the one position, the butterfly valve 19 will lie in the position illustrated in solid lines closing the air port area 33 and in an open position when air is being discharged from the valve, the butterfly valve 19 will assume the dotted position illustrated, this is due to a designed stable balance and a flat face around the apertures 31 and 32.

It is readily apparent, referring to Fig. 2, that the valve may be assembled as follows:

The butterfly valve 19 and disk 18 are first joined so that they may be retained as illustrated in Fig. 5. The disk 18 is then threadably secured to the extended threaded member 16 of the bellows 15. The member 16 is then threadably se-

cured in the socket 17 of the cap 14. This complete assembly is inserted through the housing 12 until the cap member 14 fits snugly over the end of the housing 12 and the cutout portion 27 is in alignment with the slot 34 of the cap member. By rotating the cap 14 with relation to the housing 12 until the aperture provided for pin 28 is in the position illustrated in Fig. 1, the pin 28 may then be secured to the member 12 and thus provides a stop member. When turned to the left as shown in Fig. 1, the stop pin 28 will abut against one end of the elongated slot 34 and in this position, the greatest air port opening is provided. When the cap member 14 is turned in an opposite direction, the stop pin 28 will abut with the opposite end of the elongated slot 34 and a complete closure of the air vent will be attained. It is apparent that any degree of opening may be attained by these two positions. With the barrel shaped housing 12 holding the complete valve structure as described, it may be threadably secured in the threaded socket 25 of the base 11 and with the valve so mounted, the bellows member 15 must be set so that the valve face 22 is not in contact with the valve seat 23 and thus allows free passage of air past the valve and its seat; but when heat is applied to the bellows 15 it must seat firmly on the valve seat 23 to close and prevent the passage of air or vapors through the port 24. It may be further noted that the valve is so constructed that the valve face 22 is the contact face of the steam vapors and being a part of the bellows 15; the heat acts upon the bellows to retain the valve face seated and closed. In this way the delicate convolutions of the bellows are protected from the steam vapors.

In the normal functioning of the valve as described, it is apparent that with the valve 10 threadably secured to a riser in the heating system or a radiator, when the heat in the form of hot vapors starts to rise, the cold air will pass through the valve passing the valve seat around the bellows through the port 33 of disk 18 and out past the butterfly valve 19 as illustrated in Fig. 5 passing through the cutout portion 27 and out through the elongated slot 34. At this time the positioning of cap 14 controls the degree of opening and therefore the velocity of the air flow. A full opening permits a maximum air flow. A full closing prevents the expulsion of air from the valve. The degree of opening may be regulated to control the rate of venting of air from the system. Of course the valve is primarily intended to permit a maximum required venting to insure a full venting of a particular system.

The purpose of venting valves in a system is to provide a quicker means of eliminating air from a system than is ordinarily possible by radiator air venting valves.

The purpose of this valve is to provide a variable venting orifice for balancing the venting in a heating system thus providing a means of

directing the heat first to the part of the heating system where the heat demand is greatest. Also where the demand for heat is uniform throughout the system this valve provides a means to eliminate the air from all parts of the system at the same time regardless of the position with relation to the source of heat or to the amount and size of piping. The variable orifice in this valve provides this means of obtaining a venting balance.

Various changes and modifications may be made to the valve as described without departing from the spirit of this invention and this invention shall be limited only by the appended claims.

What is claimed is:

1. In an air vent valve for a heating system a barrel shaped casing having an adjustable vent cap member supported thereon, a base portion threadably secured to said casing, a valve seat in said base portion, a thermostatic valve in said casing and extending into said base portion, a passage through said base portion, said valve seating over said passage to provide an annular chamber therebetween and being operable to engage said seat member to close said passage to flow therethrough, said valve being adjustably supported from said cap member to permit adjustment of its setting.

2. In an air vent valve for a heating system a barrel shaped casing having an adjustable vent cap member supported thereon, a base portion secured to said casing, a valve seat in said base portion, a thermostatic valve in said casing and extending into said base portion, a passage through said base portion, said valve seating over said passage to provide an annular chamber therebetween and being operable to engage said seat member to close said passage to flow therethrough, said valve being threadably supported from said cap member, said vent cap provided with an elongated slot and said casing provided with an elongated cutout portion, said vent cap adjustably mounted on said casing so that the elongated slot is in alignment with the cutout portion of said casing.
